(57) **CLAIM**

We claim the ornamental design for a battery cabinet, as shown and described.

DESCRIPTION

FIG. 1 is a front perspective view of a battery cabinet of the present invention;

FIG. 2 is a front view thereof;

FIG. 3 is a right side view thereof, the left side view being a mirror image thereof;

FIG. 4 is a top view thereof;

FIG. 5 is a bottom view thereof; and,

FIG. 6 is a cross-section view taken along the line 6—6 of FIG. 3.

The broken line showing of battery cabinet is included for the purpose of illustrating environment and forms no part of the claimed design.
